UNITED STATES PATENT OFFICE.

EUGEN TÜRCK, OF BARMEN, GERMANY.

TABLE COVER AND PROCESS FOR MANUFACTURING THE SAME.

Application filed December 22, 1925, Serial No. 77,136, and in Germany October 6, 1925.

For the manufacture of braided table covers or centerpieces it is known in the case of machine-braided lace, to draw together its inner serrated edge provided with rhombic meshes into the form of a point and thereby, by sewing its two ends together, to convert the form of the lace into that of a circular cover. By this process however only comparatively small covers have hitherto been manufactured, because half the diameter of the cover corresponded with the width of the braided lace and the latter could be manufactured only of a limited width by mechanical means.

The object of the present invention is to permit manufacture of braided covers of substantially larger diameter, indeed of any desired size, by employing in part the above described process. According to the present invention, this end is in substance attained by at least two pieces of machine-braided lace provided with such rhombic meshes being laid concentrically the one around the other and being so connected together that at the connecting edge a number of meshes of the outer lace are allotted to one mesh of the inner lace. In order to be able with advantage to effect this connection, it is recommended that, at least in the case of the inner lace, not only its inner edge but also its outer edge be provided with rhombic meshes, whereas in such lace heretofore there has always been provided an outer firm wavy edge.

Owing to the concentric arrangement of two such pieces of lace provided at their edges with rhombic meshes, it is possible, in the first place, to correspondingly enlarge the diameter of the cover. To this is added the further advantage that, owing to the diminishing curvature with increasing diameter, a further enlargement of the cover is possible by the attachment of a third piece of lace, without this added lace needing an edge formed of rhombic meshes. In this way it is possible to attach to the edge of the cover the usual braided lace provided with the more valuable ornamental patterns, and thereby to give to the cover a specially attractive appearance. Consequently a much greater abundance of patterns is producible in this way.

A braided table cover or centerpiece produced in accordance with the present in-

vention is shown by way of example in the accompanying drawing in a perspective top view.

In this drawing, *a* indicates the interior lace which is formed substantially of rhombic meshes both at its outer as well as its inner edges, of which meshes those at the inner edge are in known manner drawn together approximately to the form of a point by means of a holding thread which is conducted through the meshes at the edge, the ends of the originally strip-shaped lace web being sewn together on a radial line *A*. Concentrically surrounding the strip *a* is a second strip of lace *b* which is likewise formed substantially of rhombic meshes, especially indeed at its outer and inner edges. At the junction between strip *a* and strip *b* the meshes of the outer strip *b* are so drawn together and united that at each connection a number of them are allotted to one mesh of the inner strip of lace, in the example shown three meshes of the outer strip corresponding at each place to one mesh of the inner strip, with which one mesh the three meshes are connected by tying or sewing.

By sewing together these two concentrically adjacent strips *a* and *b* each of which has a width of 20-25 cm. a cover of about 80-100 cm. may therefore be produced. To this is thereupon connected a third strip of lace *c* which is placed likewise in circular form concentrically around the lace annulus *b* but which owing to the rapidly diminishing curvature outwardly or owing to the diminished difference in length of its edges may have been provided with firmer ornamental edges as well as highly artistic patterns, this outer strip of lace having indeed in the example shown a firm border or edge-trimming *d* at its inner edge while at its exterior it is provided with a wavy or scalloped edge *f* and in its interior portion with spots *g* worked into the lace.

In all circumstances by the employment of the new process there is no longer a limitation in any way to the size of the cover and it is not essential to provide lace with rhombic meshes in the outer portions of the cover, but there may be employed therefor lace with other highly artistic patterns. The invention is obviously not limited to the example illustrated but other embodied

ments of said invention, in particular, other forms of pattern, are possible.

I claim:—

1. A process for manufacturing table covers or centerpieces from machine-made braided lace by drawing together the lace-edge provided with rhombic meshes, characterized by at least two pieces of braided lace provided with rhombic meshes being laid concentrically the one around the other and being so connected together that at the connecting edge a number of meshes of the outer lace are allotted to one mesh of the inner lace.
- 5 2. A process according to claim 1, wherein the inner circle strip is formed of a lace whose inner and outer edge are both provided with rhombic meshes.
- 10 3. A table cover or centerpiece embodying

at least two strips of braided lace provided with rhombic meshes and disposed concentrically one about the other, the adjoining edges of the strips being united by connecting a plurality of meshes of the outer lace to each mesh of the inner lace.

20 25 30 35 4. A table cover or centerpiece embodying at least two strips of braided lace disposed concentrically one about the other, the inner strip having rhombic meshes at its inner and outer edges, the first-named meshes being drawn together and united, and the outer strip having rhombic meshes at least at its inner edge, the meshes of the adjoining edges of the strips being united by connecting a plurality of meshes of the outer lace to each mesh of the inner lace.

In testimony whereof I affix my signature:

EUGEN TÜRCK.
